UNITED STATES PATENT OFFICE.

JOHN P. WEIS, OF NYACK, NEW YORK, ASSIGNOR, BY MESNE ASSIGNMENTS, TO METROPOLITAN SEWING MACHINE CORPORATION, OF DOVER, DELAWARE, A CORPORATION OF DELAWARE.

SEWING-MACHINE.

1,295,942.

Specification of Letters Patent.

Patented Mar. 4, 1919.

Application filed March 1, 1916. Serial No. 81,303.

To all whom it may concern:

Be it known that I, JOHN P. WEIS, a citizen of the United States, residing at Nyack, in the county of Rockland and State of New York, have invented certain new and useful Improvements in Sewing-Machines, of which the following is a specification.

This invention relates to sewing machines and particularly to that class of cylinder 10 sewing machines adapted for stitching tubular goods, an object of the invention being to provide a machine for making separate rows of ornamental stitches, one row being spaced from the other to suit the requirements, and which ornamental stitches will 15 comprise a cover stitch on the bottom of the work as well as on the top thereof, together with suitable presser foot and feeding mechanisms to carry the work past the stitching 20 mechanism.

The object of the present improvement is the provision of a machine for stitching a knit strip of cloth to the shoulder of undergarments, such strip being cut with the wale 25 of the fabric, but which when stitched to the garment will have its wales at right angles to the wales of the knit garment itself so as to overcome the sagging or stretching of the shoulders thereof. A large proportion of 30 the better grade of knit underwear is made in this fashion, but this is accomplished by having the shoulder strips previously cut to a width and length to conform to the size of the garment. Then one edge thereof is 35 stitched to one side of the shoulder portion of the garment by an ornamental stitch machine, and then the opposite edge is subsequently stitched to the other shoulder portion of the garment and in this manner 40 the shoulder seams are finished. With the present improvement, however, the strip of cloth is cut in long continuous lengths and when properly rolled is suitably mounted on top of the sewing machine and guided to the 45 stitching mechanism, shown herein as a chain stitch mechanism, automatically and both seams stitched simultaneously, the throat plate being provided with suitable guides to guide the two edges of the shoulder 50 portions of the garment so that the operation is much simpler and quicker to perform and the finished work is uniform.

The invention is also useful in the manufacture of that class of undergarments made from woven fabric, such as "B. V. D.'s" 55 for instance, some of which are provided with a strip of knit goods down each leg of the garment and sometimes around the waist thereof to give elasticity to a portion of the garment, as for instance, the back 60 of the body portion and the knee of the leg portion. At present these operations are done in the same manner described in connection with the shoulder seam and, therefore, it will be apparent that a substantial 65 saving of time and expense is obtained by the use of my improvement in the manufacture of such garments and that the finished articles are more salable.

Among the objects of the invention is also 70 the provision of an improved form of looper mechanism and an improved form of thread carrying finger mechanism and means for raising and lowering the latter simultaneously with the presser foot by means of 75 which the foregoing work may be performed.

A further object of the invention is the provision of an improved thread carrying or cross stitch finger mechanism, particularly 80 useful in machines of the character described, but which may be also advantageously used in other kinds of sewing machines if desired.

A still further object of the invention is 85 the provision of an improved looper mechanism, also particularly useful in connection with the present improved machine, but which likewise may be advantageously used with other forms of sewing machines. 90

In the drawings accompanying and forming a part of this specification, Figure 1 is a longitudinal sectional view of the machine, showing the working parts and particularly the looper mechanism and the top cross 95 stitch and needle operating mechanisms. Fig. 2 is a cross sectional view of the shoulder seam; Fig. 3 is a top view of the shoulder portion of a garment, looking directly at it from the arm-hole side; Fig. 4 is a 100 detail view of the presser foot; Fig. 5 is a top view of the throat plate; Fig. 6 is an end view of the throat plate; Fig. 7 is an end view of the machine showing portions

2
of the cross stitch mechanism in section; Fig. 8 is a detail of the thread pull-off device; Fig. 9 is a perspective view of one of the looper carriers; Fig. 10 is a top cross sectional view showing the looper mechanism; Fig. 11 is an end view of the looper mechanism with the end cover thereof in section, and Fig. 12 is an enlarged view illustrating one of the rows of stitches, one of the finger thread stitches being shown slightly wider or of rope form so as to differentiate it from its companion finger thread stitch.

Similar characters of reference indicate corresponding parts in the several figures of the drawings.

As the invention is useful in connection with any cylinder machine, and particularly that shown in my application filed December 2, 1915, Serial No. 64,680, now Patent No. 1,221,254, dated April 3, 1917, a detailed description of the main part of the machine is deemed unnecessary herein.

The machine base 1 has its cylindrical bed 25 or horn 2 thereof carrying a looper shaft 3 and a feeding mechanism 4. The looper is actuated by the connections 5, while the feed is operated by the connections 6, all driven by the top rotary shaft 7. The top part of 30 the machine frame comprises a vertical trunk 8 and an overhanging arm 9 provided with bearings 10, 11 and 12. The bearing 10 carries a bushing 13, and a belt or hand wheel 14 is secured to the top shaft adjacent 35 to this bushing 13, while a tubular incasement 15 supports the forward end of this top shaft 7. The machine head 16, carrying the needle driving mechanism may be a 40 separate part from the overhanging arm 9 and clamped on to the incasement 15 in any suitable manner, as at 17, so that various stitching devices can be readily applied by substituting one head for another with the proper mechanism carried thereby. In the 45 present instance the head 16 carries a gear 18 and a crank disk 19 driven by the top shaft 7. This disk has a crank pin 20 operating the pitman 21 connected as at 22 to a cross bar 23 secured to the needle bars 24. 50 The needle bars 24 carry needle chucks 25 and needles 26 spaced to suit the character of work. Each needle bar operates in a sleeve 27, see Fig. 7, provided with a gear 28. This sleeve 27 in turn operates in a 55 similar sleeve 29 also carrying a gear 30. A collar 31 is clamped to the bottom of the outer sleeve 29, and has secured thereto a thread carrying finger 32. The inner sleeve 27 also has a collar 33 carrying a thread 60 carrying finger 34. The gears 28 of the two sleeves 27 co-act with a segmental gear 35 while the gears 30 of the two sleeves 29 co-act with a segmental gear 36. The gear 36 is in the rear of the gears 30 while the gear 35 is in the front of the gears 28 so as to give

reverse motion to the thread carrying fingers as they oscillate around the needles in the formation of the stitch. These segmental gears 35 and 36 are carried by a swinging arm 37 pivotally hung, as at 38, in the top of the machine head 16 for oscillating motion, and this arm is so shaped as to clear the other moving parts and is provided with a slot 39 in which moves a slide block 40. This block 40 is operated by a crank pin 41 carried by a large gear 42 in mesh with a smaller gear 18, forming a two to one reduction to cause the thread carrying fingers to cross the threads underneath the needles at every other stitch. In order that the thread carrying fingers may operate close to the work it is necessary to have them controlled automatically to and from the work with respect to the thickness thereof. To accomplish this the segmental gear 35 is provided with a rabbeted portion 43, overhanging the gears 28 to keep them in working relation, and to lift the fingers I have provided a lifter 44 to co-act with the collars 31 and a post 44^a carried by the presser foot mechanism, as at 45. This post has a roller 46 co-acting with the bottom portion of the segmental gear 36 to lift it.

The presser foot mechanism consists of a presser foot shank 47 having presser feet 48 hinged thereto by pins 49, see Fig. 4, and provided with guiding lips 50 to guide the shoulder strip 51 of knit cloth. These presser feet have openings 52 and tongues 53 over which the stitches are formed. It will of course be obvious that if for certain classes of work it should be desired in practice to make the presser foot in one piece instead of two, that is to say as a single bottom instead of independent bottoms as shown, such mere mechanical change does not in any way affect the invention. These presser feet are carried by the presser bar 54 secured to the presser lifter bracket 55. A guide fin 56 is also carried by the bracket 55 and operates in a slot of the head 16 to steady the movement thereof. This bracket 55 is curved as at 58 to fit underneath the arm 9 so as to occupy as little space as possible, be rigid in construction and not interfere with the work, and it is pivotally secured as at 59 to the trunk of the machine at each side thereof and has an extending arm 60 which may be operated by a chain 61 connecting with a floor treadle (not shown).

The needle bars 24 are provided with extensions 62, see Fig. 7, carrying cross bars 63 provided with thread eyes 64 for the needle threads 65. The object of having two cross bars 63 is to provide an independent adjustment thereof to properly control the threads for each stitch mechanism. The cross bars 63 co-act with the finger threads 66, see Fig. 8, as they pass through the eyes 67 of the U shaped thread guide 68, and

these thread guides 68 are mounted on posts 69 for vertical adjustment to properly control the finger threads.

From the foregoing it will be seen that two independent needle carriers are provided as well as two independent cross stitch devices coöperating therewith, a single driving mechanism for the needles and a single driving mechanism for the cross stitch fingers, and that the action or movement of the thread carrying fingers is confined close to and around the needles so as not to interfere with the handling of the work or the fingers of the operator in the manipulation thereof. In other words the present improved machine is provided with two sets or pairs of spaced or separated needles and not only does a looper coöperate with each pair of these needles but there is also a pair of thread carrying fingers coöperating with each pair or set of needles, and each thread carrying finger has a movement which, as just stated, is confined close to and around the needle, that is to say, the movement is in a circular path, almost entirely around the needle, owing to the fact that the fingers extend lengthwise of the needles and operate around the axis of the needle holders. Attached to the cylindrical bed 2 is an end bracket 70 secured to the cylinder by screws 71. This bracket is tapered toward the rear to enable the work to be removed quickly and is also in the form of an attachment so that different gages of loopers may be used to suit the needle spacings.

The looper driving shaft 3 carries a double segmental gear 72 having teeth 73 and 79, see Figs. 10 and 11, meshing with segmental gears 74 and 80 carried on short looper shafts 75 and 81, each having a looper socket hub 76, see Fig. 9, to carry a looper 77 or 83 and these hubs are cut out as at 78 to clear the needles on their downward movement. The short looper shafts are slidably supported in the bracket 70 in parallelism with the looper driving shaft 3. Each gear 74 and 80 is provided with guide plates 84 to fit close to the gear 73 and 79, see Figs. 9, 10, and 11, so that as the main looper shaft 3 is oscillated the loopers 77 and 83 will be rocked and at the same time as the main looper shaft 3 is reciprocated, such motion will be also transmitted to the loopers by reason of these guide plates 84 so that the regular four-motion movement is transmitted to the loopers so that they operate on the back of the needles in taking the needle loops and on the front of the needles while the needles are entering the looper loops. It will be understood that both loopers have the same movements as a single looper would have if it were attached directly to the shaft 3. In the present improvement the loopers, although driven by the same driving means, are separately mounted, that is to

say, both loopers are not carried by the same shaft. One of the advantages of this construction is that the loopers can be so supported that the pivotal axis of each looper is substantially intersected by the vertical axis of the needle carrying bar, with the needles of which the looper coöperates, and this enables the formation of the widely spaced rows of thread-disconnected structurally formed ornamental stitches, which could not be obtained were the loopers mounted upon the same shaft.

A feed dog 85 is carried by the feed bar 4 and operates in the slots 85 of the throat plate 86, see Fig. 5, which is secured to the bracket 70. This throat plate is provided with tongues 87 over which the stitches are formed and needle slots 88 for the needles. The front edge of the throat plate is beveled as at 89, see Fig. 6, and provided with upstanding and overhanging guides 90 to guide the shoulder portions of the work. The end cap 91 is provided to cover the looper mechanism and is held in place by pins 92, see Fig. 10.

The organization shown for operating the loopers is merely one way by which the double looper movement may be accomplished from the main looper shaft so that the loopers may be spaced one from the other, and I do not desire to be limited to the construction shown.

In Figs. 2 and 3 the work done by the machine is illustrated. The shoulder strip is 51 while the bottom portion of the garment is 100 93, 94 is the arm hole, 95 the seams joining the shoulder strip to the garment and 96 represents the top cross stitches and 97 represents the bottom stitches.

In Fig. 12 is shown one of the rows of 105 stitches in which 96' illustrates one of the finger threads while 96'' illustrates the other of the finger threads while the needle stitches are indicated by 97' and 97'' and it will be observed that each of the spaced rows of 110 stitches is made of concatenated threads in which a pair of adjacent strands of the ornamental or finger threads are in each instance overlapped and stitched down by a needle thread at each side of the row so that 115 opportunity for the raveling of the knit fabric is avoided as would be the case if only each alternative finger thread were stitched down by a needle thread.

I claim as my invention:

1. In a sewing machine of the class described, the combination of a work supporting horn, means for maintaining the opposed edges of the work supported on said horn spaced apart, means for supplying a 125 strip of material to the work to have the edges simultaneously stitched to the spaced edges of the work supported on said horn, feeding mechanism, a pair of stitching mechanisms spaced apart a greater distance than 130

the spaced edges of the work and comprising needles, a pair of loopers coöperating with the needles, and shiftable thread carrying fingers also coöperating with the needles.

5. 2. In a sewing machine of the class described, the combination of a work supporting horn, means for maintaining the opposed edges of the work supported on said horn spaced apart, means for supplying a continuous strip of material to the work to have the edges thereof simultaneously stitched to the spaced edges of the work supported on said horn, feeding mechanism, a pair of stitching mechanisms each comprising a pair of needles, said pair of stitching mechanisms being spaced apart a greater distance than the spaced edges of the work and a greater distance than the needles of each pair are spaced, a pair of loopers coöperating with the needles one with each pair thereof, and shiftable thread carrying fingers also coöperating with the needles.

3. In a sewing machine of the class described, the combination of a work-supporting horn, a pair of stitching mechanisms comprising needles, a pair of loopers coöperating with the needles, means for supplying a strip of material in the direction of the length of said horn to the stitching mechanisms for connection simultaneously with the opposed edges of a garment supported on said horn, and a throat plate having upwardly spaced guides at the front end thereof for guiding the work to which the strip is to be stitched.

4. In a sewing machine of the class described, the combination of a work-supporting horn, a pair of stitching mechanisms comprising needles, a pair of loopers coöperating with the needles, oscillatory thread carrying fingers coöperating with the needles, and means for supplying a strip of material to the stitching mechanisms for connection simultaneously with the opposed edges of a garment supported on said horn.

5. In a sewing machine of the class described, the combination of a work-supporting horn, a pair of stitching mechanisms comprising needles, a pair of loopers coöperating with the needles, oscillatory thread carrying fingers coöperating with the needles, and means for supplying a continuous strip of material in the direction of the length of said horn to the stitching mechanisms for connection simultaneously with the opposed edges of a garment supported on said horn.

6. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, and means for supplying a strip of material

to the stitching mechanisms for connection simultaneously with the opposed edges of a garment supported on said horn.

7. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, and means for supplying a continuous strip of material supported above the needles to the stitching mechanisms for connection simultaneously with the opposed edges of a garment supported on said horn.

8. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, means for supplying a continuous strip of material to the stitching mechanisms for connection simultaneously with the opposed edges of a garment supported on said horn, and means for imparting a four-motion movement to each looper.

9. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, means for supplying a continuous strip of material to the stitching mechanisms for connection simultaneously with the opposed edges of a garment supported on said horn, means for imparting movement to each looper and consisting of a looper driving shaft, a double set of segmental gear teeth carried thereby, and a pair of looper shafts in parallelism with said looper driving shaft and having segmental teeth coöperating with the looper driving teeth.

10. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, means for supplying a continuous strip of material to the stitching mechanisms for connection simultaneously with the opposed edges of a garment supported on said horn, means for imparting a four-motion movement to each looper and consisting of a looper driving shaft, a double set of segmental gear teeth carried thereby, a pair of sliding looper shafts in parallelism with said looper driving shaft and having segmental teeth coöperating with the looper

driving shaft, means connecting the looper shafts with the looper driving shaft for reciprocation with the latter, and means for reciprocating and oscillating the looper driving shaft.

11. In a sewing machine of the class described, the combination of a work-supporting horn, a pair of stitching mechanisms comprising two sets of needles, a pair of

10 loopers one coöperating with each set of needles, a pair of oscillatory thread carrying fingers coöperating with each set of needles, means for supplying a continuous strip of material to the stitching mechanisms for connection simultaneously with the opposed edges of a garment supported on said horn, means for imparting a four-motion movement to each looper and consisting of a looper driving shaft, a double

20 set of segmental gear teeth carried thereby, a pair of sliding looper shafts in parallelism with said looper driving shaft and having segmental teeth coöperating with the looper driving shaft, means connecting the 25 looper shafts with the looper driving shaft for reciprocation with the latter, and means for reciprocating and oscillating the looper driving shaft, said connecting means comprising members overlapping the meshing 30 gears.

12. In a sewing machine of the class described, the combination of needle mechanism comprising a needle and a thread carrying finger extending lengthwise of the 35 needle, a gear for oscillating said finger, and a segmental gear in mesh with said gear and pivotally supported for oscillatory movement and for rising and falling movement.

40 13. In a sewing machine of the class described, the combination of needle mechanism comprising a needle and a thread carrying finger extending lengthwise of the needle, a gear for oscillating said finger, a 45 segmental gear in mesh with said gear and pivotally supported for oscillatory movement and for rising and falling movement, and means for raising and lowering the finger and its operating means.

50 14. In a sewing machine of the class described, the combination of needle mechanism comprising a needle and a thread carrying finger extending lengthwise of the needle, a gear for oscillating said finger, a 55 segmental gear in mesh with said gear and pivotally supported for oscillatory movement and for rising and falling movement, a presser foot, and means connected therewith for raising and lowering the thread carrying finger and its operating mechanism.

60 15. In a sewing machine of the class described, the combination of a pair of stitching mechanisms including a needle and a 65 pair of thread carrying fingers, a pair of

gears for oscillating said thread carrying fingers, a segmental gear in mesh with each of said gears and pivotally supported for oscillatory movement and for rising and falling movement, and means for raising 70 and lowering the fingers and their operating means.

16. In a sewing machine of the class described, the combination of a pair of stitching mechanisms including a needle and a 75 pair of thread carrying fingers, a pair of gears for oscillating said thread carrying fingers, a segmental gear in mesh with each of said gears and pivotally supported for oscillatory movement and for rising and 80 falling movement, a presser foot, and means connected therewith for raising and lowering the fingers and their operating means.

17. In a sewing machine of the class described, the combination of a work-supporting horn, a pair of stitching mechanisms comprising two sets of needles, a pair of loopers one coöperating with each set of needles, a pair of oscillatory thread carrying fingers coöperating with each set of needles, 90 a pair of gears for oscillating each pair of fingers, and a segmental gear in mesh with each of said gears and pivotally supported for oscillatory movement.

18. In a sewing machine of the class described, the combination of a work-supporting horn, a pair of stitching mechanisms comprising two sets of needles, a pair of loopers one coöperating with each set of needles, a pair of oscillatory thread carrying 100 fingers coöperating with each set of needles, a pair of gears for oscillating each pair of fingers, a segmental gear in mesh with each of said gears and pivotally supported for oscillatory movement and for rising and 105 falling movement, and means for raising and lowering the fingers and their operating means.

19. In a sewing machine of the class described, the combination of a work-supporting horn, a pair of stitching mechanisms comprising two sets of needles, a pair of loopers one coöperating with each set of needles, a pair of oscillatory thread carrying 110 fingers coöperating with each set of needles, a pair of gears for oscillating each pair of fingers, a segmental gear in mesh with each of said gears and pivotally supported for oscillatory movement, a presser foot, and means connected therewith for raising and 115 lowering the fingers and their operating means.

20. In a sewing machine of the class described, the combination of a work-supporting horn, a pair of stitching mechanisms 120 comprising two sets of needles, a pair of loops one coöperating with each set of needles, a pair of oscillatory thread carrying fingers coöperating with each set of needles, a pair of gears for oscillating each pair of 125

5 fingers, a segmental gear in mesh with each of said gears and pivotally supported for oscillatory movement and for rising and falling movement, means for raising and 10 lowering the fingers and their operating means, and means for supplying a continuous strip of material to the stitching mechanisms for connection simultaneously with the opposed edges of a garment supported 15 on said horn.

21. In a sewing machine of the class described, the combination of a work-supporting horn, a pair of stitching mechanisms comprising two sets of needles, a pair of 15 loopers one coöperating with each set of needles, a pair of oscillatory thread carrying fingers coöperating with each set of needles, a pair of gears for oscillating each 20 pair of fingers, a segmental gear in mesh with each of said gears and pivotally supported for oscillatory movement, a presser foot, means connected therewith for raising and lowering the fingers and their operating means, and means for supplying a 25 continuous strip of material to the stitching mechanisms for connection simultaneously with the opposed edges of a garment supported on said horn.

22. A looper mechanism for a sewing machine, comprising a reciprocating and oscillating looper driving shaft, a pair of looper-carrying shafts located one at each side thereof and in parallelism therewith, and means connecting the looper driving shaft 30 with the looper shafts whereby the motion imparted to the looper driving shaft will be likewise imparted to the looper shafts.

23. A looper mechanism for a sewing machine, comprising a looper driving shaft, a 40 pair of looper-carrying shafts located in parallelism therewith, and means connecting the looper driving shaft with the looper shafts whereby the motion imparted to the looper driving shaft will be likewise imparted to the looper shafts, said connecting 45 means including two sets of segmental gears carried by the looper driving shaft and the looper shafts.

24. A looper mechanism for a sewing machine, comprising a looper driving shaft, a 50 pair of sliding looper-carrying shafts located in parallelism therewith, and means connecting the looper driving shaft with the looper shafts whereby the motion imparted to the looper driving shaft will be likewise 55 imparted to the looper shafts.

25. A looper mechanism for a sewing machine, comprising a looper driving shaft, a 60 pair of sliding looper-carrying shafts located in parallelism therewith, means connecting the looper driving shaft with the looper shafts whereby the motion imparted to the looper driving shaft will be likewise 65 imparted to the looper shafts, said connecting means including two sets of segmental

gears carried by the looper driving shaft and the looper shafts, means for holding said gears in engagement whereby during the rocking of the looper driving shaft said shafts will also be reciprocated with said 70 driving shaft, and means for rocking and reciprocating said looper driving shaft.

26. A looper mechanism for a sewing machine, comprising a looper driving shaft, a pair of sliding looper-carrying shafts located in parallelism therewith, means connecting the looper driving shaft with the looper shafts whereby the motion imparted to the looper driving shaft will be likewise 75 imparted to the looper shafts, said connecting means including two sets of segmental gears carried by the looper driving shaft and the looper shafts, means comprising guide plates located at the sides of said gears for holding the gears in engagement whereby during the rocking of the looper driving shaft said looper shafts will also be reciprocated with said driving shaft, and means for rocking and reciprocating said looper driving shaft. 80

27. Stitching mechanism for a sewing machine, comprising a needle, a slidably supported thread carrying finger extending lengthwise of the needle, a gear for oscillating said thread carrying finger, means for 85 actuating said gear, and means for raising and lowering said thread carrying finger and its gear.

28. Stitching mechanism for a sewing machine, comprising a needle, a slidably supported thread carrying finger extending lengthwise of the needle, a gear for oscillating said thread carrying finger, means for 90 actuating said gear, a presser foot, and means connected therewith for raising and lowering said thread carrying finger and its gear. 100

29. Stitching mechanism for a sewing machine, comprising needle mechanism including a needle bar, a pair of sliding sleeves 110 mounted on said needle bar, a thread carrying finger secured to each sleeve, a gear carried by each of said sliding sleeves, a pair of segmental gears in mesh with said gears, means for supporting said segmental gears 115 for oscillatory movement and for rising and falling movement, a driving shaft, means connected with the driving shaft for oscillating said segmental gears, one of said segmental gears carrying means adapted to be 120 engaged by one of the thread carrying finger gears, and means for raising the thread carrying fingers and thereby the segmental gears.

30. Stitching mechanism for a sewing machine, comprising needle mechanism including a needle bar, a pair of sliding sleeves 125 mounted on said needle bar, a thread carrying finger secured to each sleeve, a gear carried by each of said sliding sleeves, a pair 130

- of segmental gears in mesh with said gears, means for supporting said segmental gears for oscillatory movement and for rising and falling movement, a driving shaft, means connected with the driving shaft for oscillating said segmental gears, one of said segmental gears carrying means adapted to be engaged by one of the thread carrying finger gears, and means for raising the thread carrying fingers and thereby the segmental gears and comprising a presser foot.
31. In a sewing machine, the combination of a base having a work-supporting horn provided with a detachable end, looper driving mechanism carried by said horn and comprising a looper driving shaft and a pair of looper supporting shafts located in parallelism with said looper driving shaft, and means connecting said shafts.
32. In a sewing machine, the combination of a base having a work-supporting horn provided with a detachable end, looper driving mechanism carried by said horn and comprising a looper driving shaft and a pair of looper supporting shafts located in parallelism with said looper driving shaft, means connecting said shafts, said base having an overhanging arm, a detachable head for said arm, and stitching mechanism carried by said detachable head whereby one head may be substituted for another.
33. In a sewing machine, the combination of two independent needle carriers, needles carried thereby, two independent cross thread carrying fingers cooperating with the needles of each of the carriers and extending lengthwise of the needles, a single driving mechanism for the independent needle carriers, and a single driving mechanism for the cross thread carrying fingers.
34. In a sewing machine, the combination of two independent needle carriers, needles carried thereby, two independent cross thread carrying fingers cooperating with the needles of each of the carriers and extending lengthwise of the needles, a single driving mechanism for the independent needle carriers, a single driving mechanism for the cross thread carrying fingers, and means for raising and lowering the cross thread carrying fingers.
35. In a sewing machine, the combination of two independent needle carriers, needles carried thereby, two independent cross thread carrying fingers cooperating with the needles of each of the carriers and extending lengthwise of the needles, a single driving mechanism for the independent needle carriers, a single driving mechanism for the cross thread carrying fingers, and means for raising and lowering the cross thread carrying fingers and including a presser foot bar.
36. In a sewing machine, the combination of two independent needle carriers, two independent cross-thread carrying fingers co-
- operating therewith, a single driving mechanism for the independent needle carrier, a single driving mechanism for the cross-thread carrying fingers, looper mechanism comprising a driving shaft and a pair of looper-carrying shafts located in parallelism therewith, means connecting said shafts whereby the looper-carrying shafts will be oscillated and reciprocated with the looper driving shaft, and means for oscillating and reciprocating said looper driving shaft.
37. In a sewing machine, the combination of two independent needle carriers, needles carried thereby, two independent cross thread carrying fingers co-operating with the needles of each of the carriers and extending lengthwise of the needles, a single driving mechanism for the independent needle carriers, a single driving mechanism for the cross thread carrying fingers, and means for supplying a continuous strip of material to permit the same to be stitched simultaneously along both edges thereof to the work.
38. In a sewing machine, the combination of two independent needle carriers, two independent cross-thread carrying fingers co-operating therewith, a single driving mechanism for the independent needles, a single driving mechanism for the cross-thread carrying fingers, looper mechanism comprising a driving shaft and a pair of looper-carrying shafts located in parallelism therewith, means connecting said shaft whereby the looper-carrying shafts will be oscillated and reciprocated with the looper driving shaft, means for oscillating and reciprocating said looper driving shaft, and means for supplying a continuous strip of material to permit the same to be stitched simultaneously along both edges thereof to the work.
39. In a sewing machine of the class described, the combination of needle mechanism comprising a needle and a thread carrying finger extending lengthwise of the needle and supported for rising and falling movement, means supported for rising and falling movement for oscillating said finger, a presser foot, means connecting the thread carrying finger oscillating means with the presser foot, and means connecting the thread carrying finger with the presser foot whereby such thread carrying finger and its oscillating means will rise and fall with the presser foot.
40. In a sewing machine of the class described, the combination of needle mechanism comprising a needle bar adapted to carry a needle, a thread carrying finger slidably supported on said needle bar, means supported for rising and falling movement for oscillating said thread carrying finger, and means for raising and lowering the thread carrying finger and its oscillating means simultaneously.

41. In a sewing machine of the class described, the combination of a stitching mechanism including a needle bar adapted to carry a needle, a pair of thread carrying fingers extending lengthwise of the needle and slidably supported relatively to each other and to the needle bar, means supported for rising and falling movement for oscillating said thread carrying fingers, and means for raising and lowering the thread carrying fingers and their oscillating means simultaneously.

42. In a sewing machine of the class described, the combination of a stitching mechanism including a needle bar adapted to carry a needle, a pair of thread carrying fingers extending lengthwise of the needle and slidably supported relatively to each other and to the needle bar, means supported for rising and falling movement for oscillating said thread carrying fingers, and means for raising and lowering the thread carrying fingers and their oscillating means simultaneously and comprising a presser foot and means connected with the presser foot and with the oscillating means and the stitch fingers.

43. In a sewing machine having a single head, the combination of stitching mechanism comprising two sets of needles carried by said single head, a pair of loopers, one coöperating with each set of needles, and four continuously operating thread carrying fingers, a pair thereof coöperating with each set of needles.

44. In a sewing machine having a single head, the combination of chain stitch mechanism comprising two sets of needles carried by said single head, a pair of loopers, one coöperating with each set of needles, and four continuously operating thread carrying fingers, a pair thereof coöperating with each set of needles, each of said thread carrying fingers extending lengthwise of the needles.

45. In a sewing machine having a single head, the combination of stitching mechanism comprising two sets of needles carried by said single head, a pair of loopers, one coöperating with each set of needles, and four continuously operating thread carrying fingers, a pair thereof coöperating with each set of needles, each finger having a circular movement close to and substantially around each pair of needles.

46. In a sewing machine having a single head, the combination of stitching mechanism comprising two pairs of needles carried by said single head, the pairs of needles being spaced apart in said head a greater distance than the needles of each pair are spaced, a pair of loopers, one coöperating with each pair of needles, and four continuously operating thread carrying fingers, a pair thereof coöperating with each pair of needles, each finger having a circular move-

ment close to and substantially around each pair of needles whereby the fingers of each pair pass each other during their circular movement around their coöperating pair of needles.

47. In a sewing machine of the class described, the combination of a work-supporting horn, feed mechanism, a pair of stitching mechanisms comprising needles, a pair of separately mounted loopers coöperating with the needles, means for supplying a strip of material to the stitching mechanism for connection simultaneously with the spaced opposed edges of a garment supported on said horn, and shiftable thread carrying fingers coöperating with the needles, the organization of the loopers and thread carrying fingers being such that two spaced rows of ornamental stitches are formed on the top and bottom of the work.

48. In a sewing machine of the class described, the combination of a work-supporting horn, feed mechanism, a pair of stitching mechanisms comprising needles, a pair of separately mounted loopers coöperating with the needles, means for supplying a continuous strip of material to the stitching mechanisms for connection simultaneously with the spaced opposed edges of a garment supported on said horn, and shiftable thread carrying fingers coöperating with the needles, the organization of the loopers and thread carrying fingers being such that two spaced rows of ornamental stitches are formed on the top and bottom of the work.

49. In a sewing machine having a single head, the combination of feeding mechanism, a pair of stitching mechanisms comprising needles carried by said head, a pair of loopers separately mounted for movement relatively to each other and coöperating with the needles, and shiftable thread carrying fingers also coöperating with the needles, the organization being such that two structurally formed ornamental rows of covering stitches are simultaneously formed on the top and bottom of the work.

50. In a sewing machine having a single head, the combination of feeding mechanism, a pair of chain stitch mechanisms comprising needles carried by said head, a pair of loopers coöperating with the needles, and shiftable thread carrying fingers also coöperating with the needles and movable in a circular path substantially around the needles, the organization being such that two structurally formed ornamental rows of chain covering stitches are simultaneously formed, said rows being spaced apart, each row made up of concatenated threads in which each pair of adjacent strands is overlapped or stitched down by a needle thread on the top of the work.

51. In a sewing machine having a single head, the combination of feeding mecha-

nism, a pair of stitching mechanisms each comprising needles carried by said head, and means coöperating therewith for simultaneously forming two thread-disconnected, 5 structurally formed ornamental rows of stitches, each row made up of concatenated threads in which each pair of adjacent strands is overlapped or stitched down by a pair of needle threads on top of the work, so 10 that there will be two cross threads lying between each pair of needle punctures.

52. In a sewing machine having a single head, the combination of feeding mechanism, a pair of chain stitch mechanisms, each 15 comprising needles carried by said head, and means coöperating therewith for simultaneously forming two thread-disconnected, structurally formed ornamental rows of chain stitches spaced apart, each row made 20 up of concatenated threads in which each pair of adjacent strands is overlapped or stitched down by a pair of needle threads on top of the work, so that there will be two cross threads lying between each pair of 25 needle punctures.

53. In a sewing machine having a single head, the combination of feeding mechanism, a pair of stitching mechanisms each comprising needles carried by said head, 30 and means coöperating therewith for simultaneously forming two thread-disconnected structurally formed ornamental rows of covering stitches, each row made up of concatenated threads in which each pair of adjacent strands is overlapped or stitched down by a pair of needle threads on top of the work, so that there will be two cross threads lying 35 between each pair of needle punctures.

54. In a sewing machine having a single head, the combination of feeding mechanism, a pair of chain stitch mechanisms each comprising needles carried by said head, and means coöperating therewith for simultaneously forming two thread-disconnected, 40 structurally formed ornamental rows of chain covering stitches spaced apart, each row made up of concatenated threads in which each pair of adjacent strands is overlapped or stitched down by a pair of needle threads on top of the work, so that there will be two cross threads lying between each pair of needle punctures.

55. In a sewing machine having a single head, the combination of feeding mechanism, a pair of stitching mechanisms each comprising needles carried by said head, and means coöperating therewith for simultaneously forming two thread-disconnected, 45 structurally formed ornamental rows of stitches on top of the work, each row made up of concatenated threads in which each pair of adjacent strands is overlapped or stitched down by a pair of needle threads on top of the work, so that there will be two 50 cross threads lying between each pair of needle punctures.

cross threads lying between each pair of needle punctures.

56. In a sewing machine having a single head, the combination of feeding mechanism, a pair of stitching mechanisms each comprising needles carried by said head, and means coöperating therewith for simultaneously forming two thread-disconnected, 55 structurally formed ornamental rows of stitches on the bottom of the work, each row made up of concatenated threads in which each pair of adjacent strands is overlapped or stitched down by a pair of needle threads on top of the work, so that there will be two cross threads lying between each pair of 60 needle punctures.

57. In a sewing machine having a single head, the combination of feeding mechanism, needle mechanism including a plurality of sets of needles carried by said head, 65 each set comprising a plurality of needles, looper mechanism coöperating with the needle mechanism, and thread carrying mechanism also coöperating with the needles, the organization being such that two thread-disconnected structurally formed ornamental rows of covering stitches are simultaneously forming two thread-disconnected, 70 the work, each row made up of concatenated threads in which each pair of adjacent strands is overlapped or stitched down by a pair of needle threads on top of the work, so that there will be two cross threads lying 75 between each pair of needle punctures.

58. In a sewing machine having a single head, the combination of chain stitch mechanism comprising two sets of needles carried by said head, looper mechanism coöperating with the needles, and four continuously operating thread carrying fingers, a pair thereof 80 coöperating with each set of needles.

59. In a sewing machine, the combination of stitching mechanism comprising two sets of needles, a pair of separately mounted loopers, one coöperating with each set of 85 needles, and four continuously operating thread-carrying fingers, a pair thereof co-operating with each set of needles.

60. In a sewing machine, the combination of stitching mechanism comprising two sets of spaced needles, a needle bar carrying each 90 set of needles, a pair of separately mounted loopers one coöperating with each set of needles, the vertical axis of the needle bar of each set of needles substantially intersecting the pivotal axis of its coöperating looper, 95 and means coöperating therewith for forming simultaneously two disconnected ornamental rows of covering stitches spaced apart.

61. In a sewing machine, the combination of stitching mechanism comprising two sets of spaced needles, a needle bar carrying each set of needles, a pair of separately mounted loopers, one coöperating with each 100

set of needles, the vertical axis of the needle bar of each set of needles substantially intersecting the pivotal axis of its coöperating looper, and means coöperating therewith and comprising thread carrying fingers for forming simultaneously two disconnected ornamental rows of covering stitches spaced apart.

62. In a sewing machine, the combination of stitching mechanism comprising two sets of spaced needles, a needle bar carrying each set of needles, a pair of separately mounted loopers, one coöperating with each set of needles, the vertical axis of the needle bar of each set of needles substantially intersecting the pivotal axis of its coöperating looper, and means coöperating therewith and comprising a pair of thread carrying fingers coöperating with each set of needles for forming simultaneously two disconnected ornamental rows of covering stitches spaced apart.

63. In a sewing machine, the combination of a work supporting horn, stitching mechanism including looper mechanism, said looper mechanism comprising a pair of spaced-apart loopers separately mounted for movement relatively to each other and located in the free end of said horn, and means for driving said loopers.

64. In a sewing machine, the combination of a work supporting horn, stitching mechanism including looper mechanism, said looper mechanism comprising a pair of separately mounted spaced-apart loopers located in the free end of said horn, and means for driving said loopers, and comprising a driving shaft located centrally between said loopers.

65. In a sewing machine, the combination of a work supporting horn, stitching mechanism including looper mechanism, said looper mechanism comprising a pair of spaced-apart loopers separately mounted for movement relatively to each other and located in the free end of said horn, means for driving said loopers, said stitching mechanism also comprising two spaced sets of needles spaced farther apart than the

needles of each set, and thread carrying fingers coöperating with said needles.

66. A sewing machine having a driving shaft, and looper mechanism comprising a pair of sliding looper carrying shafts, a looper supported on each of said shafts, means connecting the looper shafts with the driving shaft for imparting endwise movement to the loopers, and means for oscillating the loopers.

67. A sewing machine having a driving shaft, and looper mechanism comprising a pair of sliding looper carrying shafts, a looper supported on each of said shafts, means connecting the looper shafts with the driving shaft for imparting endwise movement to the loopers, and means for oscillating the loopers, and comprising means connecting said looper shafts together whereby both are operated simultaneously.

68. In a sewing machine, the combination of needle mechanism and looper mechanism, the latter comprising a pair of loopers, a pair of shafts for supporting said loopers, means for imparting endwise movement to the shafts, and means for oscillating the loopers.

69. In a sewing machine, the combination of needle mechanism and looper mechanism, the latter comprising a pair of loopers, a pair of parallelly located shafts for supporting said loopers, means for imparting endwise movement to the shaft, means connecting the shafts, and means for rocking both of the shafts thereby to oscillate both of the loopers simultaneously.

70. In a sewing machine, the combination of needle mechanism and looper mechanism, the latter comprising a pair of loopers, a pair of endwise shiftable shafts carrying the loopers, gearing between said shafts for connecting the shafts and thereby the loopers, means for shifting said shafts endwise, and means for oscillating said loopers.

Signed at Nyack, in the county of Rockland and State of New York, this 28th day of February, 1916.

JOHN P. WEIS.
